UNITED STATES PATENT OFFICE.

CHARLES S. ELLIS, OF CHICAGO, ILLINOIS, ASSIGNOR TO THE AMERICAN COIN REGISTER COMPANY, A CORPORATION OF ILLINOIS.

COIN-BOX FOR TELEPHONES.

No. 895,443.

Specification of Letters Patent. Patented Aug. 11, 1908.

Application filed September 6, 1904. Serial No. 223,424.

To all whom it may concern:

Be it known that I, CHARLES S. ELLIS, a citizen of the United States, residing at Chicago, in the county of Cook and State of Illinois, have invented certain new, useful, and Improved Coin-Boxes for Telephones, of which the following is a description, reference being had to the accompanying drawings, forming a part of this specification, in which corresponding letters of reference in the different figures indicate like parts.

The object of my invention is to provide a simple and reliable coin-receiving and registering mechanism so constructed that the dropping of the coin into the coin slot will serve as a signal to the operator at the central station, who, upon placing a plug in the switch-board to connect with the number called for, or by pressing a button, may break the circuit with the signal light and cause the coin to drop into a position where it may either be automatically deposited in the coin receptacle or returned to the customer.

A further object is to provide positive means for actuating the coin to deposit it in the receptacle and to register the same when deposited--this act to be the result, not of the direct action of the operator at the central station, but of the customer who deposits the next succeeding coin--thereby avoiding the possibility of the operator inadvertently depositing the coin when no service has been rendered and also preventing the customer from withdrawing the coin, or otherwise improperly manipulating it.

A further object is to provide means whereby, upon the removal of the cover for the inspection or repair of the operating mechanism, the coin last deposited in the coin channel may, as a result of such removal, be deposited in the coin receptacle and properly registered, all of which is hereinafter more particularly described and definitely pointed out in the claims.

In the drawings, Figure 1, is a perspective view of a cash-box and inclosing case for registering mechanism embodying the features of my invention, Fig. 2, a front view in elevation of the registering mechanism, the case being sectioned to show the interior, Fig. 3, is a vertical sectional view upon the line 3--3, Fig. 2, as viewed in the direction of the arrow there shown, Fig. 4, is a like view showing certain parts in different relative

positions, one of the covering plates being removed to show the coin channel, Fig. 5, is a sectional view in plan taken upon the line 5--5, Fig. 3, Fig. 6, is a like view taken upon the line 6--6, Fig. 4, Fig. 7, is a like view taken upon the line 7--7, Fig. 3, Fig. 8, is a like view taken upon the line 8--8, Fig. 4, Fig. 9, is a vertical sectional view taken upon the line 9--9, Fig. 3, viewed in the direction of the arrow there shown, the parts appearing in their respective normal positions. Fig. 10, is a like view taken upon the line 10--10, Fig. 3, shewing the coin in a position to cause the closing of an electric circuit, Fig. 11, is a like view showing the gate in an abnormal position, Fig. 12, is a face view of a portion of the inside of the case showing the primary actuating slide, and Fig. 13, is a diagrammatic view showing the electric circuits, electro-magnet and swinging gate.

Referring to the drawings, 1 represents a box or case of metal, which is divided into two compartments by means of a horizontal partition 2 beneath which is an extension 3, in which is pivotally mounted a cylindrical cash box 4, having an opening 5, Figs. 3 and 4, which is normally inclosed within the casing 3, in position to communicate with a coin-slot 6 in the partition 2. A removable cover 7 is secured to the case 3 by means of a lock 8, Figs. 1 and 5 to 8 inclusive. The coin cylinder is also provided with a lock, the escutcheon of which is shown at 9^a in Fig. 1. The details of said coin receptacle, however, form no part of this invention, and I merely indicate it to show that the coin receptacle constitutes one separately locked compartment in communication with another locked compartment in which is located the registering and signal mechanism to which the coin is first introduced.

Rigidly attached to the horizontal plate 2, and to the back of the case by means of screws 9 and 10, Figs. 2, 3, 4 and 9 to 11, is a vertical metal casting generally designated 11, which extends upwardly to near the top of the case and from front to rear thereof.

Within a dovetailed groove or channel 12 is located a sliding coin actuator, generally 13, which consists of a main horizontal portion 14 having a slot 15, Fig. 4, therein adapted to receive a projection 16, Figs. 4, 5, 6, 9, 10 and 11, formed rigidly upon the casting 11 and provided with a cam 110.

or wedge-shaped surface 17, for the purpose hereinafter stated. Said projection acting alternately against the respective ends of the slot 15, forms, in addition to its more important function, a stop to limit the forward and backward movement of the coin actuator. Said actuator is provided with a vertical portion 18 which is integral with the main portion 14 and is provided with a horizontal extension 19 upon its lower end, extending rearwardly therefrom parallel with the part 14 and beneath a shoulder 20, Figs. 2 and 4, upon the upright 11. Formed upon the part 18 is a laterally projecting lug 21, which is adapted to be engaged upon one side by a lug 22, projecting from a sliding bar 23, loosely secured in guides 24, Figs. 2, 5, 6 and 12, attached to the inner side wall of the cover 7, and upon the other by the free end of a flat spring 25, the opposite end of which is attached by means of screws 26 to the bar 23.

A coiled spring 27, shown in Figs. 2 and 12, and indicated in dotted lines in Fig. 5, has one end attached to a stud 28 upon the casing and the other to an arm 29 upon the rear end of the sliding bar 23. An elongated horizontal slot 30, Figs. 1 and 2, is formed in the casing 7 through which is projected a thumb-piece 31. The spring 27 serves to hold the sliding bar 23 in the normal position shown in Figs. 5 and 12, with the thumb-piece 31 against the forward end of the slot 30 as shown in Fig. 1; and, inasmuch as the lug 21 is interposed between the boss 22 and the free end of the spring 25, the coin-actuator or slide 13 is normally held thereby in the positions shown in Figs. 3 and 5.

Formed in the part 11 is a coin channel 32 shown in Figs. 2 and 4 and indicated in dotted lines in Fig. 3, which is in registration with a coin slot 33, Fig. 1, formed in the removable cover. A depression or channel 34, Figs. 3, 4 and 9, is formed in the coin actuator slide of a depth and width to conform to that of the coin channel, so that when the actuator 13 is in its normal position as shown in Fig. 3, its walls will register with those of said coin channel. Attached to the side 50 of the part 11 by means of screws 35, is a covering plate 36 of sheet metal of irregular shape, which forms one wall of the coin channel throughout its length. Formed upon the end wall of the channel or depression in the actuator is a slight shoulder 37, shown in Fig. 4, and indicated in dotted lines in Fig. 3, which is adapted to engage one edge of a coin 38 as shown in said figure, while the other edge rests against the shoulder 39 upon the part 14 of the actuator. The channel or depression 34 in the actuator, slightly narrowed as shown, is continued into communication with a slot leading to a by-pass 40, Figs. 6, 7 and 8 into communication with a slot 41 in the case, in front of which is a wire

loop 42 adapted to engage and retain a coin as it rolls out through said by-pass. Should the proper coin be deposited, it will lodge temporarily in the position shown in Fig. 3; but a small coin or slug will fall through the slot into said by-pass, and be delivered outside of the case. Inasmuch as the shoulder 37 is very small, the opposite edges of the circular coin, especially if somewhat worn, tend to wedge very slightly between said shoulder and the shoulder 39; hence I provide a projection or shoulder 43, Fig. 3, upon the frame, and in the path of the coin as it is moved by the actuator, so that in case said coin should become so wedged, it will, upon passing over said projection, be loosened and hence free to fall by its own gravity as hereinafter described. As stated, said actuator is held in the normal position shown in Fig. 3, by means of the spring 27, and can only be moved back by pushing against the thumb-piece 31. When the coin is introduced into the slot it falls to the position shown in Fig. 3 and there rests until the user pushes back the actuator by means of said thumb-piece. During said passage, in which the coin is carried by the actuator, the rear edge and inner face of the coin is brought into contact with the cam or wedge shaped face of the part 16, until said coin is pushed laterally out of contact with the shoulder 39. The plate 36 is bent as shown at 44, Figs. 3, 5 and 6, to permit this lateral movement as more clearly shown in Fig. 6, in which the coin-actuator is shown in its extreme rear or abnormal position. This permits the coin 38 to fall into a secondary coin channel 45, better shown in Fig. 4; but in order that this may not occur until the coin actuator reaches its full backward position, I form a projection 39^a, Fig. 4, upon the actuator, against the upper edge of which the coin falls and rests until said actuator is moved back so that the forward edge of said projection is in substantial alignment with that of a vertical projection or rib 39^b, Figs. 3 and 11. When the coin is released it falls upon and is temporarily supported by a contact arm 46, as shown in said Figs. 4 and 6. Said contact-arm is pivotally connected at 47, Figs. 2 to 6 and 9 to 11 inclusive, upon an upwardly extended bent bracket 48; the lower end of which is rigidly attached to the inner face of a swinging gate generally designated by 49, also shown in Figs. 7 and 8, 120 said gate being pivotally supported by means of an arm 50, which is hinged at 51 to lugs 52 upon the side and at the rear of the part 11. The bracket 48 is insulated as shown at 53, Figs. 10 and 13, from the gate 49. A contact rod 54 is attached to the horizontal portion of the bracket 48, but separated therefrom by means of insulating material 55. The upper end of said contact rod is below and in operative prox-

imity to the contact arm 46, which latter is held normally out of contact therewith by means of a light spring 56 attached to said bracket. Mounted upon the swinging arm 50 of the gate is an armature 57, which is in operative proximity to the pole 58, of an electro-magnet 59, the terminals 60 and 61 of which are connected respectively with the metal plates 62, 63, attached as shown in Fig. 2 to an insulating plate 64, which is secured to the back plate of the case 1. Wires 65, 66 are connected with the binding-posts 67, 68, which in turn are attached to the plates 62 and 63 respectively. The wires 65 and 66 are shown in Figs. 2 as leading out of openings in the case, while in Fig. 13, the same wires are shown to be connected with the terminals of a battery 69. A normally open circuit closer 70 is interposed in the circuit described. A wire 74 leads from the bracket 48 to a binding post 72 with which, in turn, is also connected a wire 73 which is connected with the wire 66 at 74, between the battery 69 and the circuit closer 70. The contact element 54 is also connected as shown by means of a wire 75 to the wire 60 at 76. Interposed in the circuit of which the wire 73 forms a part, is a lamp 77, Fig. 13, the circuit of which is normally open. The circuit closer 70 and the lamp 77 are located at a central telephone station for the purpose hereinafter stated.

When the coin actuator is moved back as described to the full limit as shown in Fig. 4, the coin is free to fall downwardly into the coin channel 45 until it rests upon the contact arm 46 as shown in Fig. 4. The weight of the coin being sufficient to overcome the resistance of the weak spring 56, the arm 46 is caused to rest upon the end of the contact element 54, thus closing the electric circuit through the contact element 54 the wires 75, 60, 65, battery 69, wire 73, lamp 77, wire 7, bracket 48 and contact-arm 46, thereby lighting the lamp 77. Upon closing the circuit by means of the circuit closer 70, the electro-magnet 59 is energized, thereby attracting the armature 57 which causes the gate 49 to swing toward it, as shown in Fig. 8; and inasmuch as the bracket which supports the arm 46 is mounted upon the gate, said arm is drawn from beneath the coin thereby permitting the latter to descend further until it rests upon a horizontal ledge 78 extending laterally from an upright portion 79, better shown in Figs. 10, 11 and 13, which is parallel with the main body of the gate 49. The space between the two forms a coin pocket 80, the bottom of which is inclined forward to permit a coin to pass therefrom into the by-pass 40 when the gate is in an abnormal position. The gate 49 is held normally in the position shown in Fig. 7, by means of a coiled spring which is indicated in dotted lines in connection with the hinge shown at 51, and as the circuit

closer 70 is opened, the gate is caused to swing back to its normal position, when the coin falls from the ledge 78 into the pocket 80 as indicated in dotted lines in Fig. 4. The action described, of course, breaks the circuit with the lamp. It will be understood, of course, that the coin actuator, upon being released, is returned to its normal position, as shown in Fig. 3, while the coin remains in the pocket 80, which is open at both ends; but owing to the position of the gate, the opening upon one end is guarded by the rear end of the arm 19 of the actuator, which prevents the coin from rolling forward upon the inclined bottom of the pocket, while an arm 81, Figs. 3, 4, 7, 8, 10 and 11, which is rigidly attached to the end of a horizontal shaft 82, extends downwardly into the path of the coin and prevents the exit of the coin from that side except when said coin is positively pushed against said arm in the manner hereinafter described. Leading rearwardly from the pocket is a coin channel 83, Figs. 4, 7 and 8, which is in registration with the opening 6 in the bottom plate 2. The shaft 82 is supported in bearings in the part 11, and also in a vertical frame-plate 84, Figs. 2, 3 and 4 arranged parallel therewith, which plate is rigidly attached to the interior of the case by means of brackets 85, Fig. 2.

A registering mechanism of any well known and approved character may be connected with the shaft 82, but I prefer to use a registering tape 86, wound in a roll and arranged to pass downwardly through a passage-way formed by a casing 87 through a restricted opening in the plate 2 into the coin receptacle. Suitable printing and feed mechanism adapted to be actuated by the shaft 82, is also intended to be provided for actuating the tape and simultaneously printing or in some way marking or impressing a character upon said tape for each coin deposited. In addition to this a series of consecutive numbers, 86^a, Fig. 2, are printed upon the tape which passes in front of a sight opening, 86^b, Fig. 1, formed in the case. I have not shown the details of such construction as they are fully described and claimed in Letters-Patent No. 754,553, and also in application heretofore filed by Frank D. Powell and myself, Serial No. 213,326.

Pivoted upon lugs 88, Figs. 2, 3, 4, 6 and 8, is a gate or coin controller 89, having a laterally extended finger 90, Figs. 7 and 8, arranged to extend through an opening 91 in the part 11 across the entrance leading to the by-pass 40, as shown in Fig. 7. A coiled spring 92, Figs. 2, 3, and 4 serves to hold the controller in the normal position shown in Fig. 7. A cam or wedge-shaped flange 93, Figs. 2 to 9 inclusive, is formed upon the part 19 of the coin actuator in position to engage an upwardly extended lug 94, upon the free end of the controller 89, so that when said

actuator is moved back the wedge will actuate the arm 89 and cause it to be moved to the position shown in Fig. 8. Formed in the part 11 is a horizontal slot 95, Figs. 4, 5, 6 and 9, through which is loosely projected a pin 96, also shown in Figs. 2, 10 and 11, which is rigidly secured to the coin actuator. A spiral spring 27, has one end attached to the pin 96 and the other to a pin 98, Figs. 5 and 6, formed upon the part 11, the strength of which spring is less than that of the spring 27 which serves to hold the coin actuator in its normal position. A set screw 99, Figs. 3, 4 and 8, enables the controller 89 to be adjusted as hereinafter described, while a metal shield 100 forms one wall of the by-pass 40.

Having thus described the several parts of my improved device, I will now explain its operation: The user being desirous of calling a party upon the telephone with which the coin-box is adapted to be used, deposits a coin in the slot 33, the coin falling to the position shown in Fig. 3. He then pushes the thumb-piece 31 back to its full limit and releases it, when it is returned to its normal position by the action of the spring 27. The same backward and forward movement is imparted to the coin actuator 13, thereby moving the coin 38 from the position shown in Fig. 3, past the part 16, into registration with the coin-slot 45 into which it falls after having been moved laterally past the part 16 until it is free from the shoulder 39. The falling coin is arrested by the intervening contact-arm 46, which is depressed thereby as stated and brought into contact with the part 54 as shown in Fig. 10, thus completing the electric circuit with the lamp 77 at the central office, which constitutes a signal to the operator there that a coin has been deposited by the customer. The customer then calls for the desired number, whereupon either by depressing the button 70 or by "plugging in" the desired number upon the switch-board, the circuit is closed with the magnet 59 which causes the arm 46 to be withdrawn from beneath the coin, thereby permitting the latter to fall into the coin-pocket as hereinbefore stated. Should the customer fail to get the party called for, the coin may be returned to him by the operator preferably through the co-operation of the two. The operator desiring to return the coin to the customer, closes the electric circuit with the magnet 59, whereupon the gate 49 is caused to swing into the position shown in Figs. 8 and 11, when the customer may be told to take his coin. Thereupon he pushes back the thumb-piece 31, thereby moving the coin actuator and causing the wedge 93 to engage the part 94 and draw the finger 90 out of the path of the coin, which is then free to roll through the by-pass 40 into the loop 42 where the customer may take it. It is obvious that the customer cannot recover the

coin from the coin-pocket by moving the coin-actuator, as long as the gate remains in its normal position. When the controller 89 is employed the joint action of the operator and customer is required to restore the coin. Should it be found desirable to enable the operator to restore the coin unaided by the customer, it can be accomplished by removing the controller entirely or by inserting a set-screw 99, Fig. 8, which, when screwed in to a sufficient extent against the part 11, will serve to hold the part 89 in the position shown in said figure.

It is obvious that when the coin is deposited in the pocket 80, the operator is powerless to cause its deposit in the coin-box and until it is so deposited, no registration thereof can occur. As the customer cannot withdraw it without the concurrent action of the operator, it remains in the coin-pocket until the next customer deposits a coin, or until the actuator is pushed back. In order to place the second coin in the signaling position it is essential that the coin actuator should be moved to its full limit as before described. In doing this the part 19 of the coin actuator, which lies in the same plane with the coin, is pushed back against the first coin which forces the latter back into contact with the lower end of the arm 81 until the coin is freed and caused to fall into the coin channel 83 and thence into the coin receptacle 4. The tilting of the arm 81 serves to rock the shaft 82 against the action of a spring, not shown, which spring restores the shaft and arm to their respective normal positions as soon as the coin is discharged. The rocking of the shaft, however, actuates a registering mechanism to register the coin deposited. Thus it will be seen that the first coin is not registered until a second one is deposited, and that a coin always remains in the coin pocket 80 unless discharged by the movement of the actuator; and, in order to prevent a dishonest inspector, who may have access to the receptacle containing the mechanism, from appropriating this unregistered coin, the spring 97 is introduced. It will be remembered that the main actuating spring 27 is upon the inside of the cover 7. Upon unlocking said cover, it is necessary to lift it to permit its removal. This act serves to disconnect the stud 22 and spring 25 from the lug 21, whereupon the spring 97, normally under tension, as shown in Fig. 5, being free to act, immediately moves the coin actuator back to its full limit, thereby discharging the coin into the coin-box and causing its registration. The coin actuator then remains in its abnormal position as shown in Fig. 6, being retained by the spring 97. The connection between the primary and secondary actuators may be made in the following manner. Upon restoring the cover 7, the thumb-piece 31 is pushed back to its full

- limit, when the end of the spring 25 is brought into contact with and snaps over the lug 21 as shown in Fig. 6, leaving said lug between the end of the spring and the stud 22.
- 5 Upon releasing the pressure upon the thumb-piece, the powerful spring 27 acts to restore the coin actuator to its normal position against the tension of the spring 97.
- It will be seen from the foregoing that the 10 coin channel is divided into sections and that the coin must pass from one to the other in successive order before its final discharge into the coin-box; that such transfers, after the initial deposit of the coin, are accomplished by the positive action of the coin actuator which causes the registry and deposit of a coin previously introduced and the placing of the last coin introduced in a signaling position.
- 20 I do not wish to be confined to any special form of registering mechanism nor to the specific construction of other parts as it is obvious that both may be varied without departing from the spirit of the invention involved.

Having thus described my invention, I claim:

1. The combination with a coin box for telephones of a sectional coin-channel having 30 two downward and two horizontal sections, the first horizontal section leading from the end of the first downward to the entrance of the second downward section, while the second horizontal section leads past the discharge 35 end of said second downward section to an opening communicating with the coin box, a coin actuator having two members arranged to be actuated simultaneously, one in the upper and the other in the lower horizontal 40 section, means for normally supporting the coin immediately beneath the ejection opening of said secondary downward section and means for automatically returning said coin actuator to a normal position with its respective members behind the respective points of lodgment of the coins.
2. The combination with a telephone coin-box, of a coin-channel divided into stages or sections, of a manually controlled coin-actuator, one portion of which is interposed between the first and second sections of said channel to convey a coin from one to the other, while the second portion is adapted to cause the discharge of a coin from the second 55 to the third section, means for returning said

actuator to a normal position, a swinging gate having a coin pocket in normal alignment with the second and third sections of said coin-channel, a normally open electric signal circuit, a circuit closing arm upon said gate normally interposed in the path of the coin in said second coin channel section, electrical means under the control of the operator for swinging said gate, a by-pass in alignment with said pocket when the gate is in its abnormal position, means for normally closing the same and means operated from the outside of the coin-box for opening said by-pass.

3: The combination with a coin-box for 70 telephones, of a coin-channel divided into a series of separate stages or sections, a sliding coin actuator having branches or members arranged to slide in grooves formed upon different levels one above and the other below 75 the central coin section, means upon said actuator for receiving and transferring a coin from the bottom of the first to the top of the second or central coin section, a movable coin-pocket at the bottom of said central coin 80 section normally in the line of movement of said lowermost coin actuator member, a coin register, coin-controlled means between the lower end of the central and the upper end of the last coin section for actuating said registering mechanism, a by-pass, and electrical means for deflecting said coin-pocket into alignment therewith.

4. The combination with a coin-box for 90 telephones, of a coin-channel having receiving, intermediate and discharge sections respectively, of a coin-actuator under the manual control of the user, a removable cover for said box, a spring having detachable connection with said coin actuator, for yieldingly 95 maintaining the latter in a normal position when the cover is in place, and a relatively weak spring connected with said coin-actuator for moving the latter to an abnormal position when first spring is disconnected by 100 a removal of said cover.

In testimony whereof, I have signed this specification in the presence of two subscribing witnesses, this second day of September 1904.

CHARLES S. ELLIS.
